UNITED STATES PATENT OFFICE.

CARL MUEHLEISEN, OF BERLIN, GERMANY.

LINOTYPE-MACHINE.

SPECIFICATION forming part of Letters Patent No. 718,781, dated January 20, 1903.

Application filed June 19, 1902. Serial No. 112,347. (No model.)

To all whom it may concern:

Be it known that I, CARL MUEHLEISEN, a citizen of the United States, residing at Berlin, in the German Empire, have invented certain 5 new and useful Improvements in Linotype-Machines, of which the following is a specification.

The linotype-machines now in common use are provided with mechanism in which there 10 are tubes or channels for a set of matrices representing about ninety characters. It is desirable, especially for bookwork, to provide the machines with a much larger number of characters.

15 In my United States Patents Nos. 608,067 and 610,454 I have described means whereby the capacity of a linotype-machine for distributing, storing, and assembling matrices is largely increased. In said patents, however, 20 this increase was effected by duplicating the magazines and providing means for distributing to a plurality of magazines.

The present invention relates to means for increasing the capacity of single magazines, 25 whereby without increasing their size they are adapted to hold from thirty to one hundred per cent. more matrices than heretofore—that is, the number of channels in the magazines, and consequently the number of 30 different characters represented, may be increased from thirty to one hundred per cent.

The invention includes certain modifications in the matrices themselves and in the distributing devices to provide for the distribution 35 of the additional matrices.

The invention will now be described in connection with the accompanying drawings, in which—

Figure 1 is a rear view of the upper right- 40 hand corner of the magazine, showing distributing screw and rail. Fig. 2 is a similar view illustrating the operation of the distributor stop devices. Figs. 3, 4, and 5 are similar cross-sections through the distributor, illustrating its operation. Figs. 6 and 7 show the preferred manner of modifying the matrices to adapt them to the distributor. Fig. 8 is a 45 sectional view of the preferred form of the invention. Fig. 9 is a similar view of a modification. Figs. 10, 11, and 12 are details of Fig. 9. Fig. 13 is a front view of a keyboard, showing a "shift-key" device. Fig. 14 is an

edge view showing the manner of operating a double magazine. Fig. 15 is an inside view of part of the magazine. Fig. 16 is a diagram 55 in plan of the supplemental distributing-rails.

In linotype-machines as heretofore constructed the upper ends of the magazine-channels have been of uniform width, the plates at the entrances being spaced about a quarter 60 of an inch apart. The teeth or ribs on the distributing-rail were likewise arranged to drop a matrix at every quarter inch, corresponding with the magazine-entrances. I have discovered that by making the upper 65 ends of the channels of varying widths to correspond with the thicknesses of their respective matrices thirty per cent. additional matrices may be included in a magazine of the construction and width now employed, and 70 by modifying the present magazine-entrance construction I am enabled to provide double the variety of matrices now available. In my Patent No. 608,067 I proposed to increase the number of teeth in the matrices from seven 75 to eight pairs, the number of matrices which may be distributed in the standard linotype-machine being limited by the number of tooth combinations. According to the present invention I largely increase the variety of matrices which may be distributed without disturbing the ordinary seven-tooth combinations. In other words, I provide means for adapting the seven-tooth matrices for distribution in magazines containing many more 85 channels than those now in use.

Referring to Figs. 1 to 7, inclusive, of the drawings, 1 indicates the distributing-rail; 2, the rear screw; 3 4, the forward screws; 5, the pulley by means of which said screws are 90 driven, and 6 the stop-pins on said pulley. The magazine M is provided in its upper rear portion with a plate 7, hinged on pintles 8, projecting from the stationary portion of the magazine. A lever 9 is provided with a pin 95 10, adapted to intercept the pins 6 when the lever is raised by the spring 11. The pin 10 is normally held out of the path of the pins 6 by a stop 12, carried by the hinged plate 7, the rear end 13 of lever 9 normally resting on 100 said stop. The plate 7 is adapted to have a slight longitudinal movement, to facilitate which it is provided with rollers 14, resting on the pintles 8. It is normally held in the

position shown in Fig. 1 by a spring 15. When a matrix sticks in one of the magazine-entrances a succeeding matrix will engage it and move the plate 7 to the left, Figs. 1 and 2, releasing the lever 9 and immediately stopping the distributor in a manner well known.

As shown in Figs. 1 and 15, the channel-entrances are of different widths, each being but slightly wider than the thickness of the 10 matrices for which it is intended. These channel-entrances are formed by grooves 16 in the front plate of the magazine and corresponding grooves 16^a in the rear plate of the magazine and the hinged plate 7. The ears of the 15 matrices travel in these grooves. In order that the matrices may immediately enter and be guided by the grooves, the plate 7 is carried up beyond the lower ears of the matrices and provided with a transverse groove 17, in which 20 the lower ears travel as the matrices are moved along the distributing-rail. It will be seen that when a matrix is dropped its upper and lower ears are both immediately engaged with the groove in the hinged plate and a moment later with the groove in the front plate. 25 Should a matrix stick in the entrances, the distributing-screws will immediately be stopped, as heretofore explained, and the hinged plate may then be moved back, as shown in dotted 30 lines in Fig. 8, to permit the operator to dislodge the matrix.

I accomplish the result formerly attained by adding two teeth to the matrix and two ribs to the distributing-rail by providing a 35 supplementary rail 1^a, having at intervals teeth 18 and intermediate notches 19. This rail, as shown in Figs. 1 and 3, is arranged between the forward distributing-screws, its upper edge being in line with the lower edges 40 of the lugs of the matrices 20 as they travel on the rail 1.

I modify a portion of the matrices, as shown at 21 in Fig. 6, by omitting the lower corners of the upper ears on one side. A matrix so 45 constructed will drop from any part of the distributing-rail—that is, its dropping will not be interfered with by the teeth or projections of the rail 1^a. A complete matrix 20, such as shown in Fig. 3, can only drop from 50 the distributor when it registers with one of the notches 19 in the rail 1^a, as in other positions it would be intercepted by the projections 18. By this simple modification of the matrices I am enabled to double the number 55 of seven-tooth matrices which may be distributed by a single distributing-rail. I am also enabled to drop the matrices accurately in the magazine-entrances, which are just large enough to receive them. In the above embodiment of the invention two sets of matrices will have the same tooth combinations, but different characters. One set, 20, will be provided with the ordinary square upper ears and the other set, 20^a, will be provided with 60 recessed ears, as shown in Fig. 6. These two sets of matrices will be released from the rail

1 at the same point. At this point the matrices 20^a will drop into their channels. The matrices 20, however, will travel a short distance farther, resting upon one of the projections 18, and will be dropped in the adjacent channel through the succeeding notch 19.

A single rail 1^a may be used, the matrices being prevented from tipping while supported on it by resting against the lower screw 4. 70 By using two supplementary rails 1^a 1^b and cutting away one-third of the matrices on the left side and another third on the right side, as shown in Figs. 6, 7, and 8, I am enabled to distribute three sets of seven-tooth matrices 80 from a rail 1, which has the same combination now required to distribute one set. The operation of distributing three sets of matrices will be understood from the diagram of the rails 1^a 1^b. (Shown in Fig. 16.) Referring to 85 Fig. 16, it will be seen that three matrices having the same tooth combination will be dropped into the channel-entrances 16^a, 16^b, and 16^c, respectively, which are indicated in dotted lines. As the matrices reach the channel 16^a they will be released from the distributing-rail. The matrices belonging to the channel 16^a, having their rear upper ears cut away, will drop into said channel. The other two classes of matrices will be prevented 90 from dropping by reason of their rear upper ears resting on the tooth 18^b of the rail 1^b. Of the remaining matrices those having their forward upper ears cut away will be dropped into the channel 16^b, while the matrices having neither upper ear cut away will be sustained by the tooth 18^a of the rail 1^a until they 100 reach the channel 16^c, into which they will drop. In like manner there are three sets of matrices for each combination of teeth, one 105 set having their rear upper ears cut away, another set having their forward upper ears cut away, and the third set having upper ears of the usual rectangular form.

Figs. 9 to 12, inclusive, show means for distributing simultaneously into two magazines. In this form of the invention there are two magazines M' M², arranged one above the other. These magazines have common partition-plates 30, separated by a comb 31. The 115 alternate tongues of the comb 31^a are bent forward and guide the matrices into the rear magazine M², while the other tongues 31^b of the comb are bent rearward and guide the matrices into the forward magazine M'. By 120 this arrangement I am enabled to increase the capacity of the magazine to the utmost limit, as the partition-plates are thin and the spaces between them may be substantially equal to the thickness of the matrices. The magazine-channels proper, however, may be made wide enough to permit of free movement of the matrices and may have substantial ribs between them.

In Fig. 13 I have shown means for operating parts of two sets of matrices from a single set of keys. The keys operate a single

set of rods 32, which are shiftable by means of a lever 33 to cause them to register with either of two sets of rods 34, arranged upon them, the latter rods being connected with the matrix-delivery pawls. In Fig. 14 is shown a keyboard having a single set of rods 32 and a double set of rods 34, the latter connected with the escape-pawls of upper and lower magazines M' M².

10 While my invention is primarily an improvement in linotype-machines of that class in which the matrices have V-shaped serrated notches which coöperate with a distributing-rail having a V-section, it will be 15 evident that certain features of the invention are applicable to other forms of typographic machines.

I believe myself to be the first to provide an automatic distributor adapted to distribute 20 matrices into a magazine having channel-entrances of different widths, all distributors heretofore used having been adapted to drop or eject type or matrices at points uniformly spaced. In the present invention the channel entrances or throats are adjacent, being 25 separated only by thin plates of uniform thickness. The matrices are liberated from the distributing-rails when they are opposite the center lines of the entrances of their respective channels, and these center lines are 30 unequally spaced; hence the unequal spacing of the distributor-rails.

In the form of the invention illustrated advantage has been taken of the ears which occur 35 on standard linotype-matrices. Certain other matrices have been proposed having no ears, and in such cases I would provide lateral projections to be used in conjunction with the auxiliary distributor-rails.

40 What I claim, and desire to secure by Letters Patent, is—

1. In a typographic machine, a magazine having entrances of different widths to its channels in combination with a distributor 45 adapted to distribute type or matrices into said channels.

2. In a linotype-machine, in combination with matrices of different thicknesses, a magazine having entrances of different widths corresponding 50 to their respective matrices the distances from center to center of said entrances being unequal.

3. In a linotype-machine, in combination with matrices of different thicknesses, a magazine having channel-entrances of different widths, the distances from center to center of said entrances being unequal, and a distributor adapted to deliver matrices to said channels.

60 4. In a linotype-machine, the combination with a magazine having entrances of different widths, the distances from center to center of said entrances being unequal, of a main distributor-rail and a supplemental distributor-rail, for the purpose set forth.

5. In a linotype-machine, the combination

of a main distributor-rail and two supplemental distributor-rails, for the purpose set forth.

6. In a linotype-machine, the combination with the main distributor-rail having ribs 70 adapted to engage the serrated V-notches of the matrices, with a supplemental distributor-rail adapted to coöperate with the lateral projections of the matrices.

7. In a linotype-machine, the combination 75 with the main distributor-rail adapted to engage the serrated V-notches of the matrices, of supplemental distributor-rails on opposite sides of said V-notches and adapted to coöperate with lateral projections of the matrices. 80

8. In a linotype-machine, the combination with the main distributor-rail adapted to coöperate with the serrated V-notches of the matrices, of means for directing the matrices discharged from any given point on said rail 85 into a plurality of magazine-channels.

9. In a linotype-machine, the combination with a series of matrices having laterally-projecting ears and serrated V-shaped notches, of a distributor-rail engaging said notches 90 and one or more supplemental rails adapted to engage said ears, certain matrices having one ear beveled or modified to distinguish them from the remaining matrices.

10. A linotype-matrix having at its upper 95 end a serrated V-shaped notch and projecting ears on opposite sides of said notch, one of said ears being rectangular at its lower end and the other beveled or cut away, substantially as and for the purpose set forth. 100

11. A series of linotype matrices divided into groups, the matrices of one group having rectangular ears, and the matrices in one or more additional groups each having on one edge a rectangular ear and on the other edge 105 a beveled or modified ear, substantially as and for the purpose set forth.

12. In a linotype-machine, a magazine-entrance including a pivoted plate having vertically-arranged grooves to receive the matrices, and a horizontal groove to permit of the passage of the matrix-ears during the travel of the matrices on the distributor. 110

13. In a linotype-machine, a magazine and a distributor above the magazine, the rear 115 plate of said magazine being arranged to extend above the lower ends of the matrices while the latter are suspended from the distributor, said rear plate being grooved vertically to provide magazine-channels and 120 grooved horizontally to provide a passage for the lower ears of the matrices across said channels.

14. In a linotype-machine, a magazine having a hinged grooved plate forming one side 125 of the magazine-entrance, said plate being adapted to swing backward and also to slide on its pivot, for the purpose set forth.

15. In a linotype-machine, in combination with the distributor, a magazine, a hinged 130 grooved plate forming one side of the magazine-entrance, said plate being movable lat-

erally of the magazine-channels, and a distributor stop device adapted to be operated by said plate.

16. The combination with a linotype-magazine, of fixed pintles projecting laterally from the upper part of said magazine and a swinging plate mounted on said pintles, said plate being provided with roller-bearings traveling on said pintles, for the purpose set forth.

17. In a linotype-machine, a pair of stationary magazines arranged side by side and entrance-plates common to both said magazines.

18. In a linotype-machine, a magazine having channel-entrances of different widths separated by partitions of uniform thickness, whereby the distances between the center

lines of the entrances are unequal, in combination with a distributor constructed to distribute type or matrices into said channels. 20

19. In a linotype-machine, the combination of two magazines, common entrance-plates for said magazines, and a comb having its tongues alternately bent in opposite directions, said tongues being adapted to space 25 the entrance-plates and to guide the matrices into said magazines.

In testimony whereof I affix my signature in presence of two witnesses.

CARL MUEHLEISEN.
